UNITED STATES PATENT OFFICE.

AUGUST FORMON, OF PASSAIC, NEW JERSEY.

DIRECT WARPING-MACHINE.

1,252,419.

Specification of Letters Patent.

Patented Jan. 8, 1918.

Application filed April 18, 1917. Serial No. 162,880.

To all whom it may concern:

Be it known that I, AUGUST FORMON, a citizen of the United States, residing at Passaic, in the county of Passaic and State 5 of New Jersey, have invented certain new and useful Improvements in Direct Warping Machines, of which the following is a specification.

This invention relates to so-called "direct" warping machines, in which the warp, instead of being wound on a reel or the like and then re-wound onto a beam, is wound directly onto the beam, the whole warp or a considerable part of the same being treated 10 in the machine in a single operation. In these machines difficulty has always been met with in the matter of obtaining uniformity of tension on all the threads of and throughout the length of the beamed 15 warp, because the tension to which they are subjected during the warping operation has heretofore not been of a constant character. This is because after more or less material has been wound on the beam the convolutions 20 begin to cut into the previous windings, so appreciably so that the surface of the wound body, even with layers of paper or the like interposed between succeeding convolutions, will manifest to the touch distinct hollows and elevations; and of course 25 with such a formation as the surface for succeeding windings to become wound upon the latter have changing tension according as they occupy the elevations or the hollows. 30

My invention has for its object to effectually overcome this difficulty and produce a warp in a direct warping machine in which the tension will be equable throughout, and 40 this object I accomplish by constructing the reed of the machine to be traversable longitudinally of the axis of winding and providing means to traverse the reed while the winding is proceeding; thus back and forth 45 spiral windings will be produced, thereby preventing the cutting-in of the threads into the previously formed body of windings and the lack of uniformity of tension which, as explained, results therefrom.

50 My invention will be found fully illustrated in the accompanying drawings, wherein—

Figure 1 is a side elevation of the improved machine;

55 Fig. 2 is a plan view thereof;

Fig. 3 is a front elevation of the reed, its

supporting means and the means for traversing it; and

Fig. 4 is a horizontal section on line 4—4 of Fig. 3. 60

In the frame *a*, in brackets *b* adjustably supported on a pair of cross-shafts *c*, is journaled the beam *d*. One of said brackets is a housing containing gearing (shown dotted in Fig. 1) whereby the beam is driven 65 from a transverse shaft *e* journaled in the frame and operatively connected with another shaft *f*, also journaled in the frame, by bevel gearing *g*, the latter shaft being driven through friction-drive means *h* from the main shaft *i*, extending across and journaled in the frame. There is a warp-driven drum *j*, with co-acting rollers *k*, whereby a measuring means (not shown) is driven, the same and the rollers being suitably journaled in the frame; and there are also the reed *l*, supported, fixedly, by a bracket *m* projecting from the forward end of the frame, and on the frame, between said reed and the drum, a tension means designed to 70 take up the slack in the threads when the machine is stopped and consisting of a pair of suitably journaled rollers *n* and an intermediate roller *o* supported by pivoted arms *p* and capable of up and down movement, 75 the warp passing under the roller *o* and over the rollers *n*. So much is the usual construction of direct warping machines. 80

A pair of uprights *q* are arranged, side by side, on the bracket *m* between the reed *l* and the tension means, each having a transversely grooved head *q'*. In the grooves of these heads as a guide is arranged the reed *r* having a slotted downwardly projecting lug *s* with which engages 95 a pivot, in this case formed by a thumb-screw *t*, on the upper end of a lever *u* fulcrumed on another thumb-screw *v* on the bracket *m*. The lower end of this lever has suitably jointed to it the forward end of a 100 lever *w* which is fulcrumed in the frame *a*, standing horizontally, its rear end being suitably connected with one end of a pitman *x* the other end of which is connected to a wrist-pin *y* on a gear-wheel *z* journaled 105 in a bracket *2* which is bolted to the frame. This gear-wheel meshes with a pinion *3* fixed on a shaft *4* journaled in said bracket and carrying a pulley *5* around which and a pulley *6* on the shaft *f* extends a belt 7. 110

In operation, the reed is caused to traverse crosswise of the warp—specifically, length-

wise of the axis of winding—while the beam is in motion and the winding-on of the warp thereon is progressing, the motion of the reed being transmitted by the described connections between said reed and the shaft *f*. The displacement of the warp in one direction (*i. e.*, as the reed moves to the right) is shown by the broken line 8 in Fig. 2. In consequence, the windings are deposited in 10 a series of back and forth spirals, instead of each always in the same plane transverse of the axis of winding, which produces a beamed body having from start to finish a smooth uncorrugated surface and therefore 15 avoids all possibility of the threads cutting into the windings and the consequent unequalness of tension in the warp. The motion of the reed is timed, according to its 20 distance from the beam, so as to insure the windings being deposited as spirals, it being obvious that if the traverse of the reed were quick relatively to the surface speed of the wound body of warp the pitch of the 25 spirals would be reduced if the spiral winding would not be altogether prevented. The desired rate of movement of the reed may be attained by selecting gearing *z*³ of the proper relative sizes. The extent of throw of the reed may be varied by shifting the 30 fulcrum of lever *u* from one to another of the fulcrum holes *u'* provided therein as shown in Fig. 3.

I find as an incident of my invention that the traverse of the reed further prevents the 35 objectionable cutting of grooves or nicks in the rollers *n o*, the threads being caused to move laterally over the surface of each roller instead of tracking always in the same path.

40 The extent of traverse motion of the reed *r* is greater than the spacing of the threads of the warp, whereby in the spiral winding of each thread on the beam it repeatedly crosses neighboring threads on both sides of 45 it, with the result that the finished body of wound warp is in effect a single intact mass having its component parts as it were interbound or united with each other.

I place the reed *r* at the position shown, 50 to wit, so that the measuring means *j k* and tension means *n o* shall be between it and the beam for two important reasons: first, so as to insure such a distance between the reed and beam that the traverse will not 55 cause undue strain on the warp and, sec-

ond, so as to obtain the benefit of the measuring means and tension means as media to insure the threads, as they wind on the beam, actually “taking” the traverse; each traverse impulse involves a shifting of the threads over the surfaces of the tension means, measuring means and beam successively in the order named, and without these elements being interposed, with the reed far enough away from the beam to avoid unduly straining the warp even the slow traverse motion actually employed would produce in some cases too little and in others no actual displacement of the warp on the beam, according to the character of the material being warped. The acting elements (*j*, *k* and *n*, *o*) of the tension means do not contact with each other, which undesirably flattens the threads and leads to the production of streaks in the finished woven goods, but they 75 simply maintain bends in the warp, so that the threads in fact roll freely over them in shifting.

Having thus fully described my invention, what I claim as new and desire to secure by Letters Patent is:—

1. A direct warping machine including, in combination, a supporting structure, a beam journaled therein, a warp reed arranged in said structure, coacting parallel transverse members arranged between the reed and beam and out of contact with each other and maintaining a bend in the warp, and means to rotate the beam and simultaneously traverse the reed back and forth 90 lengthwise of the axis of winding, whereby the warp threads will be deposited on the beam in back and forth spirals and caused to move back and forth over the surfaces of said members. 95

2. A direct warping machine including, in combination, a supporting structure, a beam journaled therein, a warp reed arranged in said structure, a tension means and a measuring means arranged between the beam and reed and each including coacting parallel transverse members arranged out of contact with each other and maintaining a bend in the warp, and means to rotate the beam and simultaneously traverse 100 the reed back and forth lengthwise of the axis of winding. 105

In testimony whereof I affix my signature.

AUGUST FORMON.
